UNITED STATES PATENT OFFICE.

WILLIAM L. SEXTON, OF SCRANTON CITY, ASSIGNOR OF ONE-HALF TO DANIEL BARROW, OF GREENE COUNTY, IOWA.

SHOVEL FOR PLOWS.

SPECIFICATION forming part of Letters Patent No. 410,381, dated September 3, 1889.

Application filed June 14, 1889. Serial No. 314,241. (No model.)

To all whom it may concern:

Be it known that I, WILLIAM L. SEXTON, of Scranton City, in the county of Greene and State of Iowa, have invented a new and useful 5 Improvement in Shovels for Plows, of which the following is a full, clear, and exact description.

My invention consists in a transversely-divided shovel for plows or cultivators, provided with a hinge-connection of the divided portions, which are held in proper relation with each other by a break-pin attachment, substantially as hereinafter described, and pointed out in the claims, whereby in case of 15 the point of the shovel striking an obstruction such point or lower portion will be released by the rupture of the break-pin and so be allowed to drop or swing back, thereby preventing the breaking of the shovel. Such 20 construction also provides for a saving of metal in the manufacture of plow-shovels.

Reference is to be had to the accompanying drawings, forming a part of this specification, in which similar letters of reference indicate 25 corresponding parts in all the views.

Figure 1 represents a front view of a shovel embodying my invention and as attached to the leg or standard of a plow or cultivator, which is represented as broken away. Fig. 2 30 is a rear view of the same. Fig. 3 is a vertical section of the same upon the irregular line $x-x$ in Fig. 1. Fig. 4 is a transverse section upon the line $y-y$ in Fig. 1; and Figs. 5 and 6 are diagrams in illustration of the manufacture 35 of the shovel.

Referring, in the first instance, to the first four figures of the drawings, A indicates the upper or body portion of the shovel and B the point or lower portion thereof, b indicating 40 the transverse division of the shovel or blade.

Upon the back of the portion B is a casting C, which is provided with two lugs or ears $c-c$, and upon the back of the portion A is another casting D, provided with an ear d , that enters 45 in between the ears $c-c$, to form a hinge-joint having its axis in transverse relation with the shovel below the division b of the two parts A B and fitted with a hinge-pin e . These castings C and D are respectively secured to the 50 parts A and B by rivets f , or otherwise, and

the upper body part A, with its attached casting D, is further secured to the leg or standard E of the plow or cultivator, as by a bolt g , provided with a nut, or otherwise. Said castings C and D, in addition to providing 55 for the hinging of the two shovel-blade sections together, as described, constitute stiffening or re-enforcing pieces on the back of said sections and overlap one another where meeting—that is, below the division b and between it and the hinge. The overlapping portion of the one re-enforcing or hinge piece D of the body part A of the shovel-blade has a slot h in it, through which an ear i upon the underlapping portion of the re-enforcing or 60 hinge piece C passes and projects, and is perforated to receive through it a wooden pin k . This serves to lock the two hinged shovel-sections A and B and to hold them in position.

From this description it will be seen that 70 if when using the plow the point should strike an obstruction liable to damage or break the shovel, the wooden pin k , which is a break as well as a locking pin, would give way and allow the lower part B of the shovel to be thrown or 75 swung backward from the hinge-pin e as a center of motion, as shown by dotted lines in Fig. 3, and so save the shovel from breaking.

The construction of the shovel-blade, too, in independent sections, as described, will be 80 much more economical than making them in one piece, as usual. To illustrate this reference will now be made to Figs. 5 and 6 of the drawings. Thus, to make the shovel in a single piece, it will take to make two shovels; 85 say 22 inches in length from a slab of steel, A'A' in Fig. 5 indicating the two shovels and S S the waste metal which is left in producing the point ends of the shovels; but by making the shovel or shovel-blade in two parts, as described, and cutting the slab of steel, as represented in Fig. 6, to make two shovels—that is, two body parts A A and two point parts B B—but a small portion of waste metal S will be left, and a saving of steel will be 90 effected equal to half of another shovel, or thereabout, so that in cutting out a set of four shovels enough of steel will be saved to make an extra shovel, which will be equivalent to a saving of about one-fifth of the 95 100

amount of steel used in manufacturing such a set.

Having thus described my invention, I claim as new and desire to secure by Letters Patent—

- 5 1. In shovels for plows or cultivators, the shovel-blade constructed of upper and lower divided sections hinged together and held in position by a break-pin, as set forth.
- 10 2. In shovels for plows or cultivators, the shovel constructed of upper and lower sections A B, in combination with the re-enforcing hinge-pieces C D, secured to the backs of

said sections and constructed to form a hinge at the back of the lower one B of said sections, having its axis in transverse relation with the length of the shovel, also a locking attachment above the hinge adapted to receive a transverse break-pin through it, substantially as shown and described.

WILLIAM L. SEXTON.
